UNITED STATES PATENT OFFICE.

CHARLES R. LEONARD, OF NEW ROCHELLE, NEW YORK.

GARMENT.

1,022,095.

Specification of Letters Patent.

Patented Apr. 2, 1912.

Application filed July 1, 1908. Serial No. 441,499.

To all whom it may concern:

Be it known that I, CHARLES R. LEONARD, a citizen of the United States, and resident of New Rochelle, in the county of West-
5 chester and State of New York, have invented a new and useful Improvement in Garments, of which the following is a specification.

The object of this invention is to provide
10 a garment of novel construction for insuring a snug fit around the neck and, if so desired, around the wrists of the wearer to prevent the admission of rain, snow, dust or air, said novel construction including al-
15 ternating elastic and non-elastic portions at a contracted opening, the elastic portions be-
ing in juxtaposition at said opening and di-
verging therefrom in the form of gores, and an encircling elastic band surrounding said
20 opening, said elastic and non-elastic por-
tions being turned over to form a housing
for said elastic band.

The elastic encircling band is preferably made of metal such, for instance, as a me-
25 tallic endless coil spring inclosed within a housing formed by turning over the free ends of the alternating elastic and non-elas-
tic portions.

A practical embodiment of my invention
30 is represented in the accompanying draw-
ings, in which—

Figure 1 is a front view of a garment with my invention applied thereto. Fig. 2 is an enlarged detail sectional view show-
35 ing the manner of inclosing the encircling metallic elastic band within the housing formed by turning over the free ends of the alternating elastic and non-elastic portions, Fig. 3 is a detail section taken in the plane
40 of the line A—A of Fig. 2, looking in the direction of the arrows, and Fig. 4 is a sec-
tion on an enlarged scale taken in the plane of the line B—B of Fig. 1.

The body portion of the garment is de-
45 noted by 1 and it may be provided with a skirt 2 of any desired length to suit the par-
ticular requirement for which the garment is to be used.

The sleeves of the garment are denoted
50 by 3, which sleeves have their free ends con-
tracted so as to snugly embrace the wrists of the wearer. The neck of the garment is also contracted so as to snugly embrace the neck of the wearer. The garment is made
55 of non-elastic material, preferably water-

proof, so as to serve its purpose as a pro-
tection from rain, snow, etc., as well as
from dust and dirt. The neck of the gar-
ment is provided with a plurality of elastic
portions 4 alternating with non-elastic por-
tions 5. The elastic and non-elastic por-
tions are so shaped that the elastic portions
are in juxtaposition at the neck opening and
diverge therefrom in the form of gores ex-
tending into the garment for a considerable
distance. These elastic portions are of suffi-
cient length and size to permit the ready
stretching of the neck for permitting it to
be passed over the head of the wearer as the
garment is put on and taken off.

For the purpose of insuring a snug fit
around the neck of the wearer for prevent-
ing the admission of rain, snow, dust or air,
I provide an encircling elastic band 6
which is inclosed in a housing 7 formed by
turning over the free ends of the elastic
and the non-elastic portions. This encirc-
eling elastic band is preferably of metal, as,
for instance, an endless coil spring which
will retain its elasticity for a much greater
length of time than will the rubber elastic
portions of the garment. If so desired, each
of the sleeves 3 may be provided with a
similar construction, the elastic portions 8
alternating with the non-elastic portions 9
and the encircling elastic band 10 being in-
closed in a housing 11. In this construction
also, the elastic portions 8 are in juxtapo-
sition at the sleeve opening and diverge
therefrom as, for instance, upwardly into
the sleeve for a sufficient distance to permit
the hand to be passed through the sleeve
opening. The encircling elastic band 6
serves also to prevent undue stretching of
the elastic portions at the neck or sleeve of
the garment.

What I claim is:—

1. A garment having a contracted open-
ing for embracing a part of the body of the
wearer composed of alternating elastic and
non-elastic portions, the elastic portions be-
ing in juxtaposition at the said opening and
diverging therefrom in the form of gores,
and an encircling elastic band surrounding
the said opening, said elastic and non-elastic
portions being turned over to form a hous-
ing for said elastic band.

2. A garment having a contracted neck
composed of alternating elastic and non-
elastic portions, the elastic portions being in

juxtaposition at the neck opening and diverging therefrom in the form of gores, and an encircling elastic band surrounding the neck opening, said elastic and non-elastic portions being turned over to form a housing for said elastic band.

5 In testimony, that I claim the foregoing

as my invention, I have signed my name in presence of two witnesses, this 16th day of June 1908.

CHARLES R. LEONARD.
